UNITED STATES PATENT OFFICE.

TOZABURO SUZUKI, OF SUNAMURA, JAPAN.

PILED VACUUM EVAPORATING APPARATUS.

SPECIFICATION forming part of Letters Patent No. 764,393, dated July 5, 1904.

Application filed March 10, 1904. Serial No. 197,523. (No model.)

To all whom it may concern:

Be it known that I, TOZABURO SUZUKI, a subject of the Emperor of Japan, residing at No. 401 Jibeishinden, Sunamura, in the county of 5 Minami-Katsushika, in the Province of Tokio, Japan, have invented certain new and useful Improvements in Piled Vacuum Evaporating Apparatus, of which the following is a specification.

10 The invention relates to evaporating apparatus consisting of two sets of vacuum evaporating-pans placed side by side and having each a number of evaporating parts one above the other, condensed liquid evaporated by the 15 action of steam of the first pan to be transferred to the second pan, where it is further evaporated and condensed by utilizing the vapor produced in the first pan as heating agency.

20 The invention consists, first, in making the evaporating-surfaces almost as wide as the heating-surfaces and in uniformly distributing the liquid on the heating-surfaces so as to facilitate and to make complete the process of evaporating by causing the liquid gradually and automatically to drop; second, in revolving the distributing-disk so as to cause the liquid to spread uniformly over the heating-surfaces and to make the evaporating action 25 complete, the construction of the said distributing-disk being also made very simple; third, in placing one above the other the layers of the evaporating-surfaces to minimize the spaces and to simplify the construction 30 and repair and the addition or diminution of the number of the layers; fourth, in preventing the boiling over of the liquid, and, fifth, in making the evaporation of the liquid complete by utilizing the heat to its fullest extent.

40 In the accompanying drawings, Figure 1 is a front elevation of the first evaporating-pan. Fig. 2 is a longitudinal section of the second evaporating-pan. Fig. 3 is a plan view of 45 the apparatus connecting the first and second evaporating-pans. Fig. 4 is a transverse section upon line IV IV of Fig. 2. Fig. 5 is a transverse section upon line V V of Fig. 2, showing the arrangement of the coils.

50 Like numerals of reference refer to same or

similar parts throughout the specification and drawings.

The first and second vacuum evaporating-pans being entirely identical in their interior construction, the description of one will suffice for the description of the other, and numerals upon one may be taken as reference characters for the other.

The evaporating-pan consists of base 1, a number of superposed drums 11, upper drum 7, and cover 21, hermetically secured one above the other in due order. The upper drum 7 is provided with vacuum-gage 12 and thermometer 13 in order to determine the degree of 60 vacuity and temperature, while each drum 11 is provided with peep-window 14, of glass plate, on each opposite side in order to permit examination of the condition of the interior. One of the drums has a hole bored to receive the air-pipe 15, provided with an air-cock for 70 the purpose of admitting air into the pan, while the base 1 and the lowest drum are provided with a water-gage consisting of glass pipe 43 and 44, connected by cocks 41 42. Through the center of the base rises short vertical shaft 2, hermetically packed by a suitable gland, and alongside said shaft is a liquid-discharge pipe or draw-off pipe 3. The cover 21 has the outlet-port 22 in order to discharge air and vapor from the pan, while cap or 80 baffle 23 is suspended from the cover to prevent the liquid from entering the outlet-port with the vapor.

The feed-pipe 8 is connected with the upper drum 7 and is attached to the annular liquid-discharge pipe or sprinkler 9, having a number of perforations. The drums 11 are provided with flanges 47 to admit their being placed one upon the other. The drums have flat bottom 17 in their interior, which in the 90 center of each drum are provided with an annular upwardly-projected flange, so that they may form receivers. Each receiver 17 is provided with discharge-nipple and cock 19, having handle 18 outside the pan, so as to regulate 95 the quantity of the flowing liquids. Overflow-pipes 20 rise to a distance from the bottom to keep the body of the liquid constant and of suitable depth thereon, the overflow going to a perforated plate or disk beneath.

Receivers in the drums 11 are provided with a number of annular coils 26, which, as shown in Fig. 5, are connected at one end with steam-chamber 27 and at the other with exhaust-chamber 28. These chambers send their respective branches 45 46 outside of the pan in order to admit steam into the coils 26 and exhaust it therefrom. As these coils serve the purpose of giving heat to the liquid, they 10 may be replaced by other multitubular water-heater contrivances.

The upper part of the pan is provided with a rotary distributing plate or disk 30. This distributing-disk 30 is a flat annular vessel having inner and outer flanges 31 32 and is penetrated by a number of conducting-perforations 33, passing directly over the convolutions of the coils 36. These perforations have slightly-upstanding flanges in order to cause 15 the liquid to retain more or less depth in the distributing-disk 39, the overflow going over these flanges down to the next layer or receiver. In the floor of the distributing plates or disks 30 smaller perforations 34, Fig. 4, 20 than the conducting-perforations 33 are provided in order to cause the liquid to continually drip. The perforations 34 being very small, the liquid that continually flows from above cannot all escape through them, but 25 settles in the disk until it overflows the flanges of the conducting-perforations 33 and is uniformly delivered to the receiver beneath. When the supply of liquid from above is 30 stopped, all the remaining liquid in the disk 35 drips through the small perforations 34 till the disks are exhausted in a short time. The inner upstanding annular edge 31 of the distributing-disk 30 is provided with arms which are connected with vertical supports or shaft- 40 sections 36, provided in the center of the vacuum-pan. These supports are hollow and are perforated all around with steam-conducting perforations 38. Each of these supports is placed on the vertical shaft 2 one above the 45 other, so as to make them continuous and capable of being revolved by means of dowels 37, connecting the series. A short shaft 24 is fixed to the support 36 of the uppermost distributing-disk 30 and is journaled in the 50 bearing-bar 10, provided in the upper drum of the vacuum-pan 7.

In this invention two vacuum-pans constructed as in the foregoing paragraphs are installed side by side. First vacuum-pan 55 draws in steam from the steam-pipe 4, provided with pressure-gage 6, and exhausts it through the exhaust-pipe 5 after it passes first through the branch pipes 45 to coils 26 and then through the branch pipes 46 to exhaust-pipe 5, the end of which is connected with condenser and air-pump by means of steam-trap. The air-outlet port 22 of the first vacuum-pan is connected with the conducting-pipe 29. The vapor produced in the first 65 pan is led to exhaust-pipe 39 from branch

pipes 45 after first reaching coils 26 from conducting-pipe 29 and branch pipes 45. The extreme end of the exhaust-pipe is joined by the stop-valve 40 with the exhaust-pipe 25 of the second pan and is connected with condenser and air-pump. The outlet 22 of the second pan is connected with condenser and air-pump via exhaust-pipe 25. The discharging-pipe 3 of the first pan is connected with the feeding-pipe 8 via regulating-valve 108, 75 while the discharging-pipe 3 of the second pan is connected with exhaust-pump.

Steam-conducting pipe 4, steam-exhausting pipe 5, conducting and discharging pipes 25 and 39 are of the same length or twice the 80 length of the drums with which they are connected, and, as in the case of the drums, they can easily be increased or decreased in length or detached for repair.

In order to evaporate liquid by this apparatus, the condenser and air-pump at the ends of exhaust-pipes 25 39 are set in action, by which means the air contained in the first and second pans is exhausted. Then the regulating-valve 108 of the feeding-pipe 8 is opened 85 to send a suitable amount of liquid to the first pan. Steam of required volume is also sent to the same pan by opening the regulating-valve 104 of the steam-pipe to heat the coils 26, and gentle rotation is then given to the 90 vertical shaft 2. The liquid passes down through the small perforations of the distributing-pipe 9 to the upper distributing-disk 30 and accumulates there until it overflows the upper edge of the liquid-conducting 95 perforations 33 and drops down equally and uniformly on the different parts of coils 26, which generate sufficient evaporating action, and into the receiver beneath. The vapor ascends through the space between the 100 inner annular flange 16 of the receiver and the space between the inner edge 31 of the distributing-pan. By opening the cock 19 of the receiver by means of the handle 18 from outside the pan the liquid in the receiver 105 passes down through the cock 19 into the distributing-disk of the next layer. By these successive operations the liquid finally settles 110 on the base 1, and the amount of settled liquid can be examined by glass tube 43 by opening 115 cocks 41 42, provided to the water-gage.

In order to ascertain the density of liquid passing through the first pan, the cock 19 of the lower layer is closed, while the cock 42 is so adjusted as to be partly closed. The liquid 120 then fills in the water-gage. By opening the cover 44 the pycnometer is inserted in the water-gage or some quantity of the liquid is taken out, and the density can easily be ascertained in that way. After the density of 125 the liquid has been ascertained the cover is closed and the cocks 41 42 are opened.

The vapor produced in the first pan ascends by passing through the spaces between flange 16 of the receiver and between inner edge 31 130

of the distributing-disk 30, through the inner chamber of its support 36 and enters the conducting-pipe 29 by way of the outlet 22. As this vapor passes through the coils 26 of the second pan and joins, through exhaust-pipe 39, to the exhaust-pipe 25 of the second pan, thence to be conducted to the condenser, therefore by the adjustment of valves 40 the 5 vacuity of the first pan can be made lower in degree than that of the second pan. According to actual experiment the proper relative 10 vacuity of the first pan is less than fifteen inches, while the second is not less than twenty. As the relative degree of vacuity of the first and second pans is different, therefore the liquid 15 settled on the base of the first pan can automatically be sent in suitable quantity by the proper adjustment of the regulating-valve 208 from discharging-pipe 3 to the second pan and 20 through the feeding-pipe of the second pan. The said liquid in the second pan having been subjected to the same action as when it was in the first pan, it settles on the base 1 and is then discharged by pump through the pipe 3. 25 When, according to the kind of liquid to be treated and convenience, distributing-disk 30 is not to be rotated, the revolving motion of the vertical shaft 2 is stopped and the cocks 19 of the receivers closed. Then the liquid 30 first settling in the chamber overflows the upper edge of pipe 20 and passes down to be subjected in the receiver to the action of the heat generating from the whole parts of the coils and evaporating from the whole surface 35 of the chamber. Sometimes the distributing-disk 30 may be dispensed with.

The present invention being devised and put in operation as aforementioned, the evaporation of liquid is exceedingly rapid, for not 40 only does the entire surface of the coils 26 constitute heating-surface, and the evaporating-surface therefore practically equal that of the heating-surface, but the liquid is also constantly and uniformly spread over the coils 26 and is made to fall, subjecting automatically 45 and in regular succession to the same operation one portion after another. The distributing-disk is made to revolve constantly, so as to cause the liquid to spread uniformly and in 50 different positions over the heating-surface of the coils 26. This will make the evaporating action complete. The construction of the distributing-disks 30 is such as to admit of their 55 being placed on the vertical shaft one above the other in a series. Therefore their installation is simple, and no difficulty is experienced in bringing about the rotary motion and causing the vapor to ascend. The drums 11, steam - conducting pipe, steam - exhausting 60 pipe, &c., being constructed in sections, so that they may be put one above the other, it is possible to add new layers in the minimum space and to produce a maximum evaporating action. Besides they also possess the advantage 65 of simplicity of construction and instal-

lation, as in the case of the distributing-disks, and are capable of readily adding to or diminishing the number of layers and of quickly receiving repairs.

In an ordinary vacuum-pan the liquid is agitated and bubbled over as a result of boiling, and this priming impedes the action of evaporation, while more or less liquid is liable to be mixed and discharged with the vapor. In order to prevent this inconvenience, several 70 contrivances are made in ordinary cases; but in the present invention, the liquid being confined to the evaporator, this trouble is removed and the evaporation can be safely and perfectly made. The vapor of first pan being 75 utilized as the source of heating power for second pan while the latter is made to act as condenser for the first pan, the utilization of the heat is complete.

Having thus fully described my invention, 80 what I claim as new, and desire to secure by Letters Patent, is—

1. The combination, in a vacuum evaporating apparatus, of a receiver, heating mechanism therein, a revolving distributing-disk 90 thereabove, and means for applying liquid to said disk.

2. The combination, in a vacuum evaporating apparatus, of a series of receivers, heating mechanism in each of said receivers, a series of interposed revolving distributing-disks, 95 and means for supplying liquid to the uppermost of said disks.

3. The combination, in a vacuum evaporating apparatus, of a receiver, a heating-coil in 100 said receiver, a revolving distributing-disk having overflows arranged above said coils, and means for supplying liquid to said disk.

4. The combination, in a vacuum evaporating apparatus, of a series of receivers having 105 overflows, heating-coils in each of said receivers, a series of interposed revolving distributing-disks having overflows arranged above each of the convolutions of said coils, and means for supplying liquid to the uppermost of said disks.

5. In a vacuum evaporating apparatus, the combination with rotary distributing-disks, one above another, of a shaft for rotating them, and support-sections, one to each disk, mounted upon and detachably secured to said shaft and to each other.

6. In a vacuum evaporating apparatus, the combination with rotary distributing-disks, one above another, of a shaft for rotating 120 them, and tubular support-sections, one to each disk, having perforated walls and mounted upon and detachably secured to said shaft and to each other.

7. In a vacuum evaporating apparatus, the combination of a series of detachable drums placed one above another, a centrally-aper- 125 tured receiver carried by each drum, a heating-coil in each receiver surrounding the central aperture, a central vertical shaft, a se- 130

ries of superposed support-sections mounted upon and detachably secured to said shaft and to each other, a distributing-disk above each receiver, secured to the support-section corresponding thereto by arms having a central aperture, and means for supplying liquid to the topmost disk.

8. In a vacuum evaporating apparatus, the combination of a series of superposed receivers having overflows and drain-cocks with means for operating said cocks from the exterior of the casing, a heating-coil in each receiver, a rotary distributing-disk above each receiver, receiving the overflow of the receiver above and having overflows delivering to the heating-coils and receiver beneath, and a liquid-spreader, delivering liquid to the topmost disk.

9. In a vacuum evaporating apparatus, the combination of two vacuum-pans arranged

side by side, each having a series of receivers, and heating-coils, therein, an alternating series of rotary distributing-disks receiving from and delivering to said receivers, draw-off pipes, liquid-supply pipes, and overhead exhaust-pipes, with connecting piping and valves whereby the heated exhaust vapors and gases of the first are directed into the heating-coils of the second and the liquid products of the first led to the supply-pipe and spreader thereof.

10. The rotary distributor constructed with flanged overflow-perforations and with smaller drip-perforations through its flow.

In testimony whereof I affix my signature in presence of two witnesses.

TOZABURO SUZUKI.
